US00D614973S

(12) **United States Design Patent**
Takahashi

(10) **Patent No.:** US D614,973 S
(45) **Date of Patent:** ** May 4, 2010

(54) **WRIST WATCH CASE WITH BAND**

(75) Inventor: **Takayuki Takahashi**, Sagamihara (JP)

(73) Assignees: **Citizen Tokei Kabushiki Kaisha** (JP);
Citizen Holdings Co., Ltd. (JP)

(**) Term: **14 Years**

(21) Appl. No.: **29/352,296**

(22) Filed: **Dec. 18, 2009**

(51) **LOC (9) Cl.** **10-02**

(52) **U.S. Cl.** **D10/32**

(58) **Field of Classification Search** D10/30-39;
368/276, 281, 282, 285; D11/3, 12, 16
See application file for complete search history.
